BELL HOIST SYSTEM

Gordon Fox, Chicago, Ill., assignor to Frey Engineering Company, Chicago, Ill., a corporation of Maine

Application December 22, 1938, Serial No. 247,257

10 Claims. (Cl. 214—36)

The present invention relates to bell hoist systems.

In a blast furnace it is common practice to provide two charging bells in series at the top of the blast furnace. One of said bells, which is uppermost, is commonly termed the small bell and the other is commonly termed the large bell. The material to be charged into the blast furnace is deposited on the small bell, after which the small bell is opened to allow said material to deposit upon the large bell. After the small bell has opened a plurality of times to discharge material upon the large bell, the large bell is opened to discharge this material into the blast furnace. Only one of the bells should be open at any one time.

Various types of means have been provided for operating the large and small bells, but due to the size and weight of the parts problems have been encountered which have not been entirely solved by means now known and used.

An object of the present invention is to provide a combined hydraulic and pneumatic operating system which will be positive in operation and which will avoid slamming of the parts.

A further object is to provide bell operating means which are simple, which are positive in operation and which may be readily controlled.

A further object is to provide a bell operating system involving a reservoir of compressed air whereby even though the primary motive means, such for example as electrical supply means, should fail, nevertheless operations may be continued to a material extent.

A further object is to provide a bell operating system having the advantages above referred to which is so safeguarded that in the event of failure of the primary motive means, or of the hydraulic or pneumatic means, the result will be had that one of the bells will be automatically moved to closed position.

A further object is to provide an improved bell hoisting system well adapted to meet the needs of commercial service.

Further objects will appear as the description proceeds.

Referring to the drawing—

Figure 1 is a diagrammatic view illustrating one embodiment of the present invention; and

Figure 2 illustrates a detail of construction.

The numeral 10 indicates a blast furnace provided at the top thereof with the conical portion 11 adapted to be closed by the large bell 12. Coaxially disposed with the conical portion 11 is the conical portion 13 adapted to be closed by the

small bell 14. The numeral 15 indicates an enclosure for the top part of the furnace connecting the conical portion 11 with the conical portion 13. Said bells 14 and 12 are shown separated in the drawing for purposes of convenient illustration. According to usual practice said bells will be coaxially disposed. The large bell 12 is provided with the operating member 16, which, through the lever 17, is connected to the cable 18.

10 The numeral 19 indicates an operating cylinder for the large bell, which operating cylinder is provided with the piston 20 and the piston rod 21. Said cable 18 is connected to the upper extremity of the piston rod 21. The space below the piston

15 20 is connected to atmosphere. In order to prevent the waste of oil which may seep past the piston 20, the lower extremity of the cylinder 19 is connected through the pipe 22 to the oil reservoir 23, which is at atmospheric pressure. The

20 upper extremity of the cylinder 19 is connected through a series of piping with the oil pressure tank 24. The piping connecting the upper portion of the large bell cylinder 19 with the oil pressure tank 24 includes the pipe 25, the operating valve 26, the pipe 27 and the pipe 28. Connected in said pipe 27 is the regulating valve 29,

25 which has the function of regulating the speed of the piston 20 on its down stroke. Connected in parallel across the regulating valve 29 is the check valve by-pass 30. Connected to the oil pressure tank 24 through the pipe 28 is the pipe 31 leading to the oil reservoir 23. Disposed in said pipe 31 is the relief valve 31a. Connecting the operating valve 26 with the pipe 31 is the

30 pipe 31b provided with the regulating valve 31c.

The large bell 12 is biased to open even when unloaded. In other words, it is necessary, in order to hold the large bell 12 in closed position, to exert oil pressure upon the piston 20 in the 35 large bell cylinder 19, so that said piston 20 is at or near the bottom of its stroke.

Referring now to the operating means for the small bell 14, said small bell has connected thereto the operating member 32, which, through 40 the lever 33, is connected to the cable 34.

The numeral 35 indicates an operating cylinder for the small bell, which cylinder is provided with the piston 36 having the piston rod 37. Said piston rod 37 is stationary and is provided with 45 an axial bore 38 through which oil may be admitted to raise the cylinder 35. The lower side of the cylinder 35 is connected to the oil reservoir 23 through the pipe 38a, which may be flexible to permit movement of cylinder 35. Said cylinder 35 is provided with the counterweights

39, whereby said cylinder 35 will bias the small bell 14 to closed position even when said small bell 14 is loaded with its burden.

The numeral 40 indicates a pipe connected to the bore 38 of the piston rod 37. Said pipe 49 is connected to the operating valve 41, and the pipe 42 connects the operating valve 41 to the pipe 28 which leads to the pressure tank 24. Disposed in said pipe 42 is the regulating valve 43 for regulating the up-stroke of the cylinder 35. Said operating valve 41 is also connected through the pipe 44 to the oil reservoir 23, which is at atmospheric pressure. Disposed in said pipe 44 is the regulating valve 45 for regulating the down-stroke of the cylinder 35.

The numerals 46—46 indicate oil pumps for discharging oil from the oil reservoir 23 to the pressure tank 24, check valves 47—47 being provided between said pumps 46—46 and said oil pressure tank 24. Said pumps 46—46 are operated by the motors 48—48. The numeral 49 indicates an air pump for maintaining a predetermined pressure of air within the oil pressure tank 24, said air pump 49 being connected to said oil pressure tank 24 through the pipe 50, which pipe 50 is provided with the check valve 51. A vent valve 52 is provided to prevent the application of excess air pressure to the oil pressure tank 24. The numeral 53 indicates a pressure gauge for the oil pressure tank 24. The term "air" as used in this specification is to be construed to include gas and air.

One type of operating valve which may be used in the practice of the present invention is illustrated in Figure 2, wherein the casing 54 35 provides a cylinder for housing the operating rod 55. Said operating rod 55 is provided with the pair of pistons 56 and 57. Said pistons 56 and 57 are adapted to control the ports 58 and 59 respectively. The casing 54 is provided with the port 60 communicating at all times with the space between the pistons 56 and 57. The operating rod 55 is controlled by the piston rod 61, which in turn may be controlled by any preferred means. It will be clear that in the positions of the parts illustrated in Figure 2, communication is had between the ports 58 and 60, whereas the port 59 is closed. With the operating rod 55 in its uppermost position communication will be had between the ports 59 and 60, whereas the port 58 will be closed. The operating valve is indicated by the numeral 26.

The mode of operation of the above described embodiment of the present invention is substantially as follows: Inasmuch as the large bell 12 is not counterweighted it must be held closed by oil which fills the chamber of the cylinder 19 above the piston 20. This oil is under high pressure. In order to close the large bell 12, oil is forced from the pressure tank 24 into the upper portion of the large bell cylinder 19. This is done by movement of the operating valve 26. The speed of the downward movement of the piston 20 can be controlled by adjustment of the regulating valve 29. In its movement to close the large bell 12 the piston 20 travels downwardly in the large bell cylinder 19 until the large bell 12 seats and until tension in the bell cable places a sealing pressure on the large bell. The cable pull is determined by the oil pressure. In the event of an explosion between the bells, the pull upon the cable 18 is restricted pneumatically, because the air in the pressure tank can be practically instantaneously compressed to a degree sufficient to permit enough movement of the 75

large bell 12 to relieve the pressure on the bell. A substantial movement of the bell will not cause a great increase in pressure in the pressure tank 24 because of the compressibility of the air therein. The relief valve 31a provides for further relief through flow of oil from the pressure tank 24 through said relief valve 31a to the oil reservoir in the event that the pressure in the pressure tank rises sufficiently.

10 In the event of an explosion between the large bell 12 and the small bell 14 there will be a tendency for the large bell cable 18 to pull upward on the piston 20 in the large bell cylinder 19, thereby increasing the oil pressure in said cylinder 19. This oil pressure is transmitted directly back through the operating valve 26 and through the regulating valve 29 to the pressure tank 24. Because the regulating valve 29 serves as a restriction, the check valve by-pass 30 operates to by-pass said regulating valve 29. This permits the ready flow of oil in a direction from the large bell cylinder 19 toward the pressure tank 24. The pressure tank 24 is partly filled with oil but has a compressed air space above the oil. The compressed air space acts as a cushion which prevents any sudden impact stresses such as would otherwise be characteristic of a hydraulic system. The compressed air gives to the entire system certain desirable characteristics of a pneumatic system, particularly with reference to limiting the cable pulls and possible stresses.

15 In the event that an explosion between the large bell 12 and the small bell 14 is sufficient to substantially raise the pressure of the oil in the pressure tank 24 by compressing the air therein, the pressure will be limited by operation of the relief valve 31a, which discharges oil to the reservoir 23. In the event that an explosion causes upward movement of the piston 20 in the large bell cylinder 19, said piston will again move downwardly to close the large bell as soon as the pressure in the hopper between the bells is relieved.

20 It should be noted that no limit switches are required and that the large bell seats in a cushioned manner due to the air in the pressure tank.

25 To open the large bell 12, the operating valve 26 is operated to provide communication between the cylinder 19 and the pipe 31b to permit discharge of oil from the large bell cylinder 19 through the regulating valve 31c to the oil reservoir 23, which is at atmospheric pressure. Said regulating valve 31c can be adjusted to control the rate of movement of the large bell. The bell cylinder 19 in conjunction with the valve 31c acts as an oil dashpot to restrict the opening speed of the large bell. According to the present invention the weight of the piston 20 is negligible in comparison to the parts with which it is connected plus the burden on the large bell, and gravity is depended upon as the sole motive means for opening the large bell. This construction is to be distinguished from the construction of pneumatic hoists in which pressure is applied below the piston to lift the weight of the operating parts, plus any counterweights which may be connected thereto. The construction according to the present invention tends to start to open more quickly than a pneumatic hoist because no counterweights are used in connection with the cylinder 19 or its piston 20.

30 The small bell 14 is operated through the cylinder 35. It is preferred to counterweight the small bell 14 sufficiently to hold it closed against

maximum burden which may be imposed thereon. Thus the small bell 14 will be opened only when and if oil is introduced under pressure above the piston 36 to lift the cylinder 35, thereby permitting the small bell 14 to open by gravity.

Oil for operation of the small bell 14 is introduced to the small bell cylinder 35 through the operating valve 41 adjacent to the base thereof. The speed of opening of the small bell can be controlled by means of the regulating valve 43. The lower side of the small bell cylinder 35 is connected to the oil reservoir 23 through the pipe 38a, being thereby subjected to atmospheric pressure.

When the small bell 14 is to be closed, the operating valve 41 is moved to connect the pipe 40 with the pipe 44. The space above the piston 36 is thereby connected to the oil reservoir 23 through the regulating valve 45, and oil is permitted to pass out of the upper portion of the small bell cylinder 35 to the oil reservoir. The speed of opening of this bell can be controlled by adjusting the regulating valve 45.

In the operation of the two bells oil is taken from the oil pressure tank 24 and delivered to the oil reservoir 23. In turn oil is removed from the reservoir 23 by means of the pumps 46-46 which deliver oil back to the pressure tank 24. By delivering oil to the pressure tank 24 these pumps tend to compress the air in said tank 24 to raise the pressure therein. Incidentally the air pump 49 may be used, if necessary, to introduce air into the pressure tank 24 in the event that there is a gradual loss of air therein due to diffusion in the oil leaving said pressure tank 24.

In further explaining the functions of the air pump 49, let it be assumed that the tank 24 is empty and that the air therein is at atmospheric pressure. If oil be now delivered to this tank, the exits therefrom being closed, the air pressure within the tank will approximate twice atmospheric pressure when the tank is half full of oil. It will be evident that in order to secure a high pressure in this tank while still retaining a substantial volume of air for cushioning purposes, it is not feasible to start with atmospheric pressure in the tank.

If the above operation be repeated with air at 100 pounds pressure in the empty tank, the pressure would be approximately 200 pounds per square inch when the tank is half full of oil. Similarly, if compressor 49 is of the type which can deliver air at 200 pounds per square inch pressure, it will be possible to introduce air at such pressure into the empty tank and then by pumping oil therein to increase the pressure to about 400 pounds per square inch with the tank half full of oil.

In practice it will be preferred to use high oil pressures, and it is also desirable that the volume of the compressed air, suitable for cushioning purposes in tank 24, be substantial. In order to accomplish these relations the compressor 49 is provided, which functions to deliver air at an initial increased pressure to the empty tank, using pumps 46 as booster pumps to further increase the air pressure of the air cushion in reservoir 24.

It will be observed that in the operation of the bells there is a tendency to reduce the pressure within the pressure tank 24. Continued operation would eventually drop the pressure in the pressure tank below operative adequacy. However, by suitably proportioning the pressure tank with reference to the volume of the bell cylinders 19 and 35, the air compressed in the pressure tank

serves as a reserve motive means whereby the system can be operative to a limited extent without reference to the pump. This is an important feature as it gives a degree of reliability in that operation of the bells is not dependent upon electric power or any external source of power, so long as adequate pressure remains within the tank 24. During the time that the large bell 12 is being closed, oil flows from the pressure tank 24 to the large bell cylinder 19 at a high rate. This action occurs only for a short period, such as in the neighborhood of ten or twenty seconds. This period is normally followed by a much longer period during which material is being deposited upon the large bell. The rate of delivery of oil from the pumps 46-46 to the pressure tank 24 is much less than the rate of flow from the pressure tank 24 to the large bell cylinder 19. Such a relation is possible because of the fact that the large bell cylinder is in movement only a small fraction of the total time. Because of the relationship just mentioned, a small motor and a pump equipment, operating not necessarily continuously but operating a large portion of the time, serves to supply the motive power for the entire system. The peak demands, caused by movement of the large bell, are not transmitted directly back to the electrical system, nor is it necessary to supply a large motor and a heavy mechanism capable of handling such a short time peak load. A motor equipment is perhaps one-fifth the size of the motor that would be required to handle the load directly without the introduction of the compressed air feature which serves as a power storage means.

As previously stated, the large bell 12 is biased to open and is kept closed only by the oil pressure within the large bell cylinder 19. If the oil pressure should fail, the large bell would open. The small bell is biased to closed position even when burdened, and is caused to open by reason of application of oil pressure. Therefore, in the event of failure of the oil pressure the small bell will close and will remain closed. Therefore the advantage is had that in the event of a failure of oil pressure one of the two bells will be closed.

The hydro-pneumatic hoist system hereinabove described requires relatively small cylinders and is adapted to have a compact arrangement. No large counterweight is required for the large bell, and for at least a short period of time the system may be independent of the electric supply or other outside power supply. It involves the use of no limit switches and permits cushioned seating of the bells and limited cable pulls.

Though a preferred embodiment of the present invention has been described in detail, many modifications will occur to those skilled in the art. It is intended to cover all such modifications that fall within the scope of the appended claims.

What is claimed is—

1. In a bell hoist system, in combination, a pair of bells in series with each other, each of which moves upwardly to close and downwardly to open, a bell cylinder for operating one of said bells, a bell cylinder for operating the other of said bells, said one bell requiring a certain amount of pressure in its corresponding cylinder to maintain same closed even when unloaded, said other bell being biased to closed position even when loaded, a pressure tank adapted to contain liquid and compressed air, a reservoir for liquid, means for selectively directing liquid from said pressure tank to said cylinder for said one bell or for directing liquid from said first-mentioned cylinder to said

reservoir, means for selectively directing liquid from said pressure tank to said cylinder for said other bell or from said last mentioned cylinder to said reservoir, and means for returning liquid under pressure from said reservoir to said pressure tank, whereby a circulation of oil is had between said reservoir and said pressure tank by reason of the elevating and lowering of said weighted member.

2. In a bell hoist system, in combination, a pair of bells in series with each other, each of which moves upwardly to close and downwardly to open, a bell cylinder for operating one of said bells, a bell cylinder for operating the other of said bells, said one bell requiring a certain amount of pressure in its corresponding cylinder to maintain same closed even when unloaded, said other bell being biased to closed position even when loaded, a pressure tank adapted to contain liquid and compressed air, a reservoir for liquid, means for selectively directing liquid from said pressure tank to said cylinder for said one bell or for directing liquid from said first-mentioned cylinder to said reservoir, means for selectively directing liquid from said pressure tank to said cylinder for said other bell or from said last-mentioned cylinder to said reservoir, means for returning liquid under pressure from said reservoir to said pressure tank, whereby a circulation of oil is had between said reservoir and said pressure tank by reason of the elevating and lowering of said weighted member, and regulating valves for controlling the flow of liquid from said cylinders to said reservoir.

3. In a bell hoist system, in combination, a pair of bells in series with each other, each of which moves upwardly to close and downwardly to open, a bell cylinder for operating one of said bells, a bell cylinder for operating the other of said bells, said one bell requiring a certain amount of pressure in its corresponding cylinder to maintain same closed even when unloaded, said other bell being biased to closed position even when loaded, a pressure tank adapted to contain liquid and compressed air, a reservoir for liquid, means for selectively directing liquid from said pressure tank to said cylinder for said one bell or for directing liquid from said first-mentioned cylinder to said reservoir, means for selectively directing liquid from said pressure tank to said cylinder for said other bell or from said last-mentioned cylinder to said reservoir, means for returning liquid under pressure from said reservoir to said pressure tank whereby a circulation of oil is had between said reservoir and said pressure tank by reason of the elevating and lowering of said weighted member, and regulating valves for controlling the flow of liquid from said pressure tank to said cylinders.

4. In a bell hoist system, in combination, a pair of bells in series with each other, a bell cylinder for operating one of said bells, a bell cylinder for operating the other of said bells, a pressure tank adapted to contain liquid and compressed air, a reservoir for liquid, means for selectively directing liquid from said pressure tank to said cylinder for said one bell or for directing liquid from said first-mentioned cylinder to said reservoir, means for selectively directing liquid from said pressure tank to said cylinder for said other bell or from said last-mentioned cylinder to said reservoir, and relief means for directing liquid from said pressure tank to said reservoir in the event of an explosion between said bells.

5. In a bell hoist, in combination, a bell upon which material is deposited progressively over a period of time to build up a load, means for con-

trolling the elevation of said bell comprising an operating cylinder and a pressure tank, said pressure tank being adapted to be partly filled with liquid and partly filled with compressed air, a certain amount of pressure being necessary in said cylinder to maintain said bell closed even when said bell is unloaded, a reservoir for liquid, means for selectively directing liquid from said pressure tank to said cylinder or directing liquid from said cylinder to said reservoir, and means for increasing the pressure within said pressure tank at a rate sufficient to hold said bell in closed position in spite of increase of the weight of said bell and the material deposited thereon, said pressure increasing means including pumping means for delivering liquid from said reservoir to said pressure tank.

10 6. In a bell hoist system, in combination, a pair of bells in series with each other, an operating cylinder for one of said bells, a second operating cylinder for the other of said bells, said one bell requiring a certain amount of pressure in its corresponding cylinder to maintain said one bell closed even when unloaded, said other bell with its corresponding cylinder being provided with counterweights to hold said other bell in closed position even when loaded, and common pressure means for introducing fluid selectively into said cylinders for controlling the elevation of said cylinders and consequently the positions of said bells.

20 7. In a bell hoist, in combination, a bell upon which material is deposited progressively over a period of time to build up a load, means for controlling the elevation of said bell comprising an operating cylinder and a pressure tank, said pressure tank being adapted to be partly filled with liquid and partly filled with compressed air, a certain amount of pressure being necessary in said cylinder to maintain said bell closed even when said bell is unloaded, a reservoir for liquid, means for selectively directing liquid from said pressure tank to said cylinder or directing liquid from said cylinder to said reservoir, and means for increasing the pressure within said pressure tank at a rate sufficient to hold said bell in closed position in spite of increase of the weight of said bell and the material deposited thereon, said pressure increasing means including pumping means for delivering liquid from said reservoir to said pressure tank, the volumetric capacity of said pressure tank being such that sufficient liquid may be delivered therefrom to said cylinder to close said bell without aid from any extraneous source of power.

30 8. In a bell hoist, in combination, a bell upon which material is discharged progressively to build up a load, an operating cylinder for said bell, a certain amount of pressure being required in said cylinder to hold said bell closed even when said bell is unloaded, a pressure tank adapted to be partly filled with liquid and partly filled with compressed air, and means for introducing fluid into said cylinder from said tank whereby an initial relatively low pressure is applied to close said bell and the pressure is increased to retain the bell in closed position while material is being loaded upon said bell.

40 9. In a bell hoist system, in combination, a pair of bells in series with each other, an operating cylinder for one of said bells, a second operating cylinder for the other of said bells, a certain amount of pressure being required in said first mentioned cylinder to maintain said one bell closed, the other of said bells being biased to

closed position, a pressure tank adapted to contain liquid and compressed air, a reservoir for liquid, means for selectively directing liquid from said tank to said one cylinder or from said one cylinder to said reservoir, means for selectively directing liquid from said tank to said second cylinder or from said second cylinder to said reservoir, and means for returning liquid under pressure from said reservoir to said pressure tank whereby a circulation of oil is had between said 10 reservoir and said pressure tank by reason of the elevating and lowering of said bells.

10. In a blast furnace, in combination, a pair of bells in series with each other, the pressure in the space between said bells being adapted to be relieved by opening movement of one of said bells, 5 hydraulic means for holding said one bell in closed position, and pneumatic means associated with said hydraulic means to cushion the shock produced when said one bell is forced open by an explosion between said bells.

GORDON FOX.
